UNITED STATES PATENT OFFICE.

ARTHUR B. BELLOWES, OF PITTSBURG, PENNSYLVANIA.

SWITCH-STAND.

SPECIFICATION forming part of Letters Patent No. 724,659, dated April 7, 1903.

Application filed October 9, 1902. Serial No. 126,496. (No model.)

To all whom it may concern:

Be it known that I, AETHUR B. BELLOWES, a citizen of the United States, residing at Pittsburgh, in the county of Allegheny and State of Pennsylvania, have invented or discovered certain new and useful Improvements in Switch-Stands, of which improvements the following is a specification.

The invention described herein relates to certain improvements in a form or construction of switch-stand forming the subject-matter of an application filed September 3, 1902, and numbered serially 121,949.

The invention is hereinafter more fully described and claimed.

In the accompanying drawings, forming a part of this specification, Figure 1 is a sectional elevation of my improved switch stand or box. Fig. 2 is a plan view, portions of the cover and of the vertical shaft being broken away. Fig. 3 is a detail view of the vertical shaft. Fig. 4 is a vertical sectional view, the plane of section being indicated by the line IV IV, Fig. 2. Fig. 5 is a view similar to Fig. 4, illustrating a modification of the invention; and Fig. 6 is a sectional elevation on a plane indicated by the line VI VI, Fig. 5.

In the practice of my invention the mechanism except the operating-lever is inclosed within a case or shell consisting of a bottom portion 1, provided on opposite sides with lugs or flanges 2, to which the top or cover 3 is secured by bolts 4, said top or cover having laterally-projecting flanges 5, whereby the box or case may be secured on the ends of cross-ties or other suitable foundation. A transmitting-shaft 8 is provided at its ends with journals 7 and 14, the journal 7 being arranged within a socket or step-bearing 6, forming the bottom portion of the box or case. The upper journal 14 is arranged in suitable bearings in the top of the case or cover, and a spindle 14^a for the reception of the target and lamp extends from the upper end of journal 14 of the shaft. The portion of the shaft within the case or shell is provided with laterally-projecting walls or wings 11, with which an inclined member extending from a radial arm on the operating-shaft, as the arm 10, engages, so that on the laterally shifting of said arm the shaft will be axially rotated. It is preferred that an antifriction-sleeve 10^a

should be loosely mounted upon the portion of the arm lying between the wings.

The outer end of the arm 10 is so connected to the radial arm 17 as not to move relative thereto, as by forming the arm 10 integral with the crank-arm, as shown in Fig. 4, or the arm 10 may be formed with an angular pin 16, engaging a similarly-shaped socket or opening in the crank-arm, as shown in Fig. 6. The radial arm 17 is formed on or secured to the driving-shaft 18, which is shown with its journal portion arranged in suitable bearings 19, formed partly in the lower portion of the case or shell and partly in the cover. An operating-lever 21 is connected with the outer end of the shaft 18, preferably in the manner described in the application above referred to, in order that a hand-lever 21 can have a movement of approximately ninety degrees or to a vertical position before any considerable exertion is required to shift the switch.

The shaft 8 is provided with an arm 23, extending laterally therefrom and adapted to be connected to the switch-rod 24, preferably by means of a pin 25, as described in the application referred to, said pin extending into a slot in the switch-rod, as shown.

It is characteristic of the construction shown in Figs. 1 to 4, inclusive, that the arm 10 is simply in engagement with the wings on the vertical shaft and has no pivotal connection whatsoever therewith, but is free to turn while being shifted laterally, the antifriction-sleeve facilitating such axial rotation or movement between the wings.

In the construction shown in Figs. 5 and 6 the arm 10 is provided with a ball 9 at its inner end, and the shaft 8 is constructed as described in the application referred to, with suitable-shaped socket formed in the sections of such shaft, said sections being held together by the cover of the case or shell.

The arm 10 is rigidly connected to the crank-arm 17, so as to move laterally therewith, but without any axial movement of the arm, and the relative change of position of the arm and vertical shaft 8 necessary in such lateral movement being permitted by the loose engagement connection of the arm with such shaft. It will be observed that the arm 10 and crank-arm 17 form two sides of a triangle the base of which coincides with the axis of

the operating-shaft 18 and that such baseline or prolongation of the axis of shaft 18 forms the axis of rotation of the arm 10 and radial arm 17. It is characteristic of the improvement described herein that the radial arm on the operating-shaft has an inclined connection, as the arm 10, to the vertical shaft and that this inclined connection is integral with the radial arm in the sense that 10 said connection has no movement relative to the radial arm.

I claim herein as my invention—

15 1. A switch-stand having in combination a switch-rod, a vertical shaft connected to the switch-rod, an operating-shaft having a radial arm and integral therewith, an inclined connection to the vertical shaft said connection being at an angle less than a right angle to the radial arm, substantially as set forth.

20 2. A switch-stand having in combination a

switch-rod, a vertical shaft connected to the switch-rod and provided with wings, an operating-shaft having a radial arm and integral therewith, an inclined member engaging said wings on the vertical shaft said member being at an angle less than a right angle to the radial arm, substantially as set forth. 25

3. A switch-stand having in combination a switch-rod, a vertical shaft connected to the switch-rod and provided with wings, an operating-shaft and integral therewith an inclined arm pivotally connected to the vertical shaft and engaging said wings, substantially as set forth. 30

In testimony whereof I have hereunto set 35 my hand.

ARTHUR B. BELLows.
